SPLIT LOCK REPLACER

Joseph Sunnen, Kirkwood, Mo.

Application April 10, 1931, Serial No. 529,066

1 Claim. (Cl. 81—3)

This invention relates to new and useful improvements in lock replacers, for use in connection with valve assemblies of internal combustion engines.

5 As is well known in the art, the valve stem carries on its lower end a spring washer which is locked thereon by a suitable key or lock. Considerable difficulty is experienced in replacing the lock members in position on the stem particularly when split lock members are used.

The primary objects of the present invention are to provide a tool which is highly efficient in operation, is so constructed that it can be used with ease in restricted locations, and which is adapted to hold the respective halves of the lock in operative positions independently of each other.

Other objects of the invention are to provide a tool of the class described having a pair of co-operating jaws, each of which is adapted to receive and resiliently hold in operative position one of the complementary lock members independently of the other so that said jaws can be moved relatively to each other without danger of releasing said lock members.

25 Still other objects of the invention are to provide a split lock replacer comprising a support, a movable member on said support, and a pair of opposed jaw members pivotally mounted on said movable members and yieldingly held in closed position, said jaw members being pivotally movable independently of each other and each being provided with a spring for holding the respective lock member in proper position whereby the pivotal movement of said jaw members away from each other does not cause displacement of said lock members.

Additional objects of the invention are to provide a tool of the class described having cooperative pivotally mounted jaws for yieldingly holding in operative positions, and independently of each other, the complementary lock members, said jaws being movable longitudinally relatively to a fixed member to cause said jaws to move automatically apart and clear the valve stem after said split lock members have been placed in position thereon.

With these and other objects in view, my invention consists in certain novel features of construction and arrangement of parts, hereinafter more fully described and claimed, and illustrated in the accompanying drawings, in which—

Figure 1 is a side elevational view of my tool and showing it in connection with a valve assembly, the valve spring being shown in dotted lines.

Figure 2 is a top plan view of the tool.

Figure 3 is an enlarged vertical cross section taken on line 3—3 of Figure 1.

Figure 4 is an enlarged vertical cross section taken on line 4—4 of Figure 2.

Figure 5 is an enlarged horizontal cross section taken on line 5—5 of Figure 1.

Figure 6 is a vertical cross section taken on line 6—6 of Figure 5.

Figure 7 is a top plan view of the tool showing the jaw members thereof in expanded positions.

Referring by numerals to the accompanying drawings, A indicates a conventional valve assembly, partly broken away, wherein B indicates a valve stem, the lower end of which is provided with a seat C for receiving the split lock members D. These members are split longitudinally and when assembled are of truncated cone-shape and fit into a downwardly presented similarly shaped seat formed on washer E. This washer is loosely arranged on said valve stem and is engaged by the lower end of a valve spring F which serves to hold said washer upon said lock members and the latter in turn holds said members on the valve stem.

The valve assembly is generally so located with respect to the engine block that due to the limited space and the particular construction of the valve assembly it is extremely difficult to replace the lock members on said valve stem.

To facilitate placement of the lock members, I provide a tool comprising a support 10 having a handle 11 and carrying a sliding plate 12 on which are pivotally mounted jaw members or levers 13.

The support 10 is pivotally mounted at its rear end on one end of handle 11, as indicated at 14. This support is preferably offset in its length, as indicated at 15, in order to bring the other end 16 of said support on a different horizontal plane 95 with respect to pivot 14 and handle 11. This end 16 has secured thereto, by means of a rivet 17, sliding plate 12. The lower end of this plate is formed channel shaped with the flanges 18 presented downwardly and engaging the sides of end 16 whereby said plate 12 is maintained during its sliding movement in proper alignment with said end. This plate is formed with a longitudinally disposed slot 19 through which rivet 17 extends upwardly and which permits sliding movement of said plate relatively to support 10.

Jaw members or levers 13 are pivotally mounted adjacent to the rear end of sliding plate 12 as indicated at 20. Each lever has its own pivot and

said pivots being spaced equidistant to each side of the longitudinal axis of the device.

Each lever is preferably formed from a blank of sheet metal so cut and shaped as to provide a 5 horizontally disposed bottom wall 21 flanged at the sides 21a, 21a, a vertically disposed inner wall 22, and a horizontally disposed top wall 23, which latter terminates a suitable distance from the forward or jaw end of the lever. Thus the 10 rear half of each lever is substantially U-shape in cross section, while the forward half of the lever is substantially angle shape. Rivet 17 extends upwardly a suitable distance above the top walls 23 of the levers and is provided with a 15 washer 24 which bears against said walls and prevents upward movement of said levers without hampering movement thereof in horizontal planes, the vertical walls 22 being also cut away at these points to provide notches sloping in both 20 directions. These notches are of sufficient depth to permit said levers, when sliding member 12 is retracted, to occupy closed positions, as shown in Figures 2 and 5. However, when said plate is moved forwardly, cut-out portions 25 are disengaged from the rivet, thereby causing said levers to spread apart or occupy open positions as shown in Figure 7.

As the ends of levers 13 project a short distance beyond the pivots 20, the inner sides of 30 said levers are disposed obliquely, as indicated at 27, in order to permit opening movement of said levers. Preferably a U-shaped spring 28 is used to hold the levers in closed position. This spring extends inwardly between the horizontal 35 walls 21 and 23 of the levers and its ends bear against the vertical walls 22 of the respective levers, thereby yieldingly maintaining the latter in closed positions (see Fig. 5).

Each lever is provided near its forward or jaw 40 end with a semi-circular notch 29 formed in the inner edge of the bottom wall 21, the vertical wall 22 terminating adjacent to each side of said notch. Each of these notches is of smaller radius than the outside radius of the corresponding lock 45 and of slightly greater radius than the inner radius thereof, so that the corresponding lock members can be easily supported on the levers with their concave faces aligned and without any 50 danger of interference between the lever and the valve stem of the valve assembly.

Each lever is provided with a resilient member 55 or spring 30, the rear end of which is engaged by pivot or pin 20 of the respective lever, while a projection 31 formed integral with the upper wall 60 23 and extending downwardly therefrom engages said member at the opposite side and at a point spaced a suitable distance from pivot 20. The forward end of the spring is provided with a convex face which bears against the inside of the 65 vertical wall 22a, which latter is arranged between notch 29 and the extreme end of lever 13. Thus each lever is pivotally mounted independently of the other lever and is provided with an individual resilient member which is not associated in any manner with the other lever.

Each resilient member 30 is provided near its 70 forward end with a seat portion 30a having a substantially semi-circular seat or face 32 which is arranged adjacent to the notch 29 of the respective lever.

When a split lock member D is placed in position on the lever, the vertical face thereof bears against the inner sides of the wall portions 22 and 22a while the outer convex face thereof is engaged by the seat 32 of resilient member 30 and is thus held in operative position on the lever.

The tension of spring 28 exerts pressure against levers 13 and causes them normally to occupy closed positions, the levers automatically adjusting themselves so as to bring the notches 25 midway of pin 17. When pressure is applied to the levers longitudinally, as when the forward ends thereof are pressed against the valve stem, said levers through the movement of pin 17 are caused to move apart to clear said stem. This automatic opening and closing of the jaw members of the levers facilitates the operation and positioning of the device.

In the operation of my improved split lock replacers the split locks D, D are inserted between the walls 22, 22a and seat portion 30a of each spring 30 for application to the seat C of valve stem B. However, before the split lock may be inserted the spring F is raised by means of a suitable tool (not shown) so that the washer E is above the seat C on which the split locks D, D are placed. With the spring raised the operator may now push the levers 13, 13 against the valve seat C so as to force the levers open and allow the stem to enter the notch 29 and of course between the split locks D, D. The forward ends 30a, 30a of springs 30, 30 bear against the split locks D, D with sufficient pressure to hold them on the seat C as the operator withdraws the entire tool, the two split locks slipping out from behind the forward ends 30a, 30a of the springs. It is preferable before removing the tool that the valve spring F be released so that seat C will engage the split locks D, D and absolutely hold them against displacement when the tool is being withdrawn.

I claim:

A split lock replacer comprising a support, a plate movably mounted thereon and provided with a longitudinally disposed slot, a pair of levers pivotally mounted near one of their ends on said plate and having their opposite ends extending beyond said plate and provided with oppositely disposed jaws adapted to receive a pair of split lock members, a yieldable member arranged on each lever and having its free end arranged to cooperate with the respective jaw and yieldably hold the corresponding split lock member in position thereon, a spring for yieldably holding said levers in jaw closing positions, and a pin fixed to and extending upwardly from said support through the slot of said plate and between said levers whereby said plate and parts associated therewith are movable longitudinally of said support and said pin, the inner edges of said levers being provided with opposed cooperating notches for accommodating said pin and permit closing of said jaws when said levers occupy normal positions, said pin causing outward movement of said jaws when said plate and said levers are displaced longitudinally.

JOSEPH SUNNEN.
